Primary Examiner — Dana Meyrow(74) *Attorney, Agent, or Firm* — Crowell & Moring LLP(57) **CLAIM**

The ornamental design for a bottle, as shown and described.

DESCRIPTION

FIG. 1 is a perspective view of a bottle showing my new design;

FIG. 2 is a front view thereof, the rear view being identical; FIG. 3 is a right side view thereof, the left side view being identical;

FIG. 4 is a top view thereof; and,
FIG. 5 is a bottom view thereof.

The broken lines illustrate environmental structure and form no part of the claimed design.

The drawings include surface shading that represents contour and not surface ornamentation.

FIGS. 1–5 illustrate a transparent embodiment.
